UNITED STATES PATENT OFFICE.

MILTON E. RIEMER, OF ST. JOSEPH, MISSOURI.

STEERING MECHANISM FOR AUTOMOBILES.

1,069,810.

Specification of Letters Patent. Patented Aug. 12, 1913.

Application filed December 2, 1912. Serial No. 734,523.

To all whom it may concern:

Be it known that I, MILTON E. RIEMER, a citizen of the United States, residing at St. Joseph, in the county of Buchanan and 5 State of Missouri, have invented certain new and useful Improvements in Steering Mechanisms for Automobiles, of which the following is a specification, reference being had therein to the accompanying drawing.

10 My invention relates to improvements in that class of steering mechanisms which are applied to the steering knuckles of automobiles, now generally in use, and has special reference to improvements on the form of 15 mechanism set forth in Letters Patent No. 935,610, of September 28, 1909.

The objects of my improvements are, to so construct said steering mechanism, that the same may be applied to steering knuckles, 20 the pivotal points of which are so close to the wheels of the vehicle as to prevent the securing of cams thereon.

Further objects are, to so construct and 25 arrange the parts of said mechanism that the same shall be simple, substantial and durable, and efficiently perform all of the offices set forth in the Letters Patent cited.

Still further objects are, to so construct said mechanism, that the steering cams and 30 cam rotating means, may be situated at points distant from the knuckles.

I attain these objects by the mechanism illustrated in the accompanying drawing, in which:—

35 Figure 1 is a top plan of the preferred form of the mechanism, certain portions of the frame being broken away to avoid unnecessary extension of the drawing. Fig. 2 is a front elevation of the parts seen in Fig.

40 Fig. 3 is a top plan of the parts, as they appear when rotated clock-wise to the extreme point of their movement. Fig. 4 is an enlarged vertical section, on the line X X, seen in Fig. 5, looking downward. Fig. 5 45 is a horizontal section of a cam, on the line Y Y, seen in Fig. 4, looking upward. Figs. 6 and 7 are top plans of two of the other various forms in which the knuckle rotating means may be constructed.

50 Referring to Fig. 1, 1 designates certain portions of the frame of the vehicle. Front axle 1' may form a part of said frame, or be indirectly connected therewith in different ways, in various types of vehicle construction, and since said frame is only a secondary element of the invention, the same is

neither fully shown nor described. The vehicle wheels 2 and 2' are attached to the bifurcated ends 1'' of axle 1', by knuckles 3 and 3', the inner ends of which, are mounted 60 between said bifurcations, on pivot bolts 4. Said bolts are passed through said bifurcations and said knuckles. These knuckles are each provided with a pair of grooved segments 5, of semicircular form secured thereon or formed therewith. Said segments are adapted to receive flexible pulling members 6. Steering cams 7 and 7' are rotatably mounted on axle 1'. Said cams may be mounted on forwardly extending brackets 70 not shown. These cams are of elongated elliptical form, the longitudinal axes of the ellipses being inclined toward each other in a forward direction, and being at such inclination to the axle 1', and of such proportional width and length as to cause proper difference in the movement of wheels 2 and 2', as hereinafter described. This proper difference of movement is such that the planes of said wheels are always at right angles to the pivot point on which said vehicle is turning. Said pivot point, not shown, would be at the point where the dot and dash lines 2'' would intersect, if the same were extended, see Fig. 3. Rigidly mounted on 80 cams 7 and 7' respectively, are two reversed segments 7''. These segments are of the same form as segments 5, and are mounted in alignment with them, and have their semicircular grooved edges toward said segments 85 5. These edges are adapted to receive the inner end portions of flexible members 6. Said members have their outer ends secured to segments 5, are extended inward therefrom, are crossed over each other and have 90 their inner ends secured to segments 7'', for reversely transmitting the movement of cams 7 and 7', to knuckles 3 and 3', and their respectively attached vehicle wheels. The edge faces of said cams are suitably grooved 100 or channeled, for the reception in said channels of the hereinafter described flexible members.

Since cams 7 and 7' are alike in their construction and operation, a detailed description of one cam is sufficient. Referring to Figs. 4 and 5, cam 7 has depression 7^a formed in the bottom of its channel and has slot 7^b and pivot aperture 7^c formed therethrough. The point in said channel, in which said depression is formed, is a matter of importance; it should be in the outward side and 110

near the rearward end of cam 7, in order to freely permit the hereinafter described flexible members to be operated.

Flexible pulling member 8 passes continuously around cams 7 and 7', (see Figs. 1 and 2,) and is secured thereto by stirrups 9 which press said member into depressions 7^a, as seen in Figs. 4 and 5. Stirrup 9 is held in place by bolt and nut 9'; said bolt being passed through the apertured ends of said stirrup and through said slot 7^b.

Rearward from the center of axle 1', the shaft 11' is rotatably mounted in a portion of frame 1. Said shaft has winding drum 11 rigidly secured on the lower end portion thereof, while hand wheel 11'' is secured on the upper end of said shaft. Flexible drawing members 12 are wound in a plurality of coils around said drum and have their rear ends secured thereto. The forward end of said members 12 are respectively passed around opposite sides of grooved idle pulleys 13, are crossed and have their forward ends secured respectively to cams 7 and 7', by the heretofore described member securing means, as seen in Figs. 4 and 5. Said pulleys 13 are rotatably mounted on another portion of frame 1, directly in front of drum 11 and adjacent to flexible member 8. Said idle pulleys form guiding means for member 12. From this arrangement it should be understood, that if the hand wheel 11'' is rotated in the direction indicated by arrow 16, that the rear end portions of member 12 will be unwound from, and wound on drum 11, as indicated by arrows 17. The crossed front portions of said members will move as indicated by arrows 18. By this means cams 7 and 7' are rotated in the direction indicated by the last mentioned arrows. This rotation of said cams is reversely conveyed to knuckles 3 and 3' and their respectively attached vehicle wheels 2 and 2', by the previously described reverse rotating means. When said hand wheel 11'' is thus rotated to the limit of its rotation, said vehicle wheels will be in the position seen in Fig. 3.

It will be seen, that in moving the parts, as previously described, the front portion of member 8 is unwound from the contracted outer side portion of cam 7, and is wound onto the elongated end portion of cam 7', thereby causing cam 7 and the thereby reversely rotated knuckle 3, to rotate farther than cam 7' and its reversely rotated knuckle 3'. This unequal rotation of said knuckles, brings about the before described movement of their respectively attached vehicle wheels 2 and 2', in such manner, that said wheels are always in the proper plane, as before described.

While I have described the preferred form of knuckle rotating means, as shown in Figs. 1, 2, and 3; it is evident that other knuckle

rotating means, of various forms, could be used, without departing from the spirit of my invention. Two of such other forms are shown in Figs. 6 and 7. In the form seen in Fig. 6, knuckle 3 has segment 21 secured thereon, provided with gear teeth 21' on its semicircular edge. Cam 7 has segment 22 secured thereon and provided with gear teeth 22' on its semicircular edge; said teeth being in engagement for transmitting rotation of 75 said cam to said knuckle.

In the form of knuckle rotating means, seen in Fig. 7, knuckle 3 has cross-arm 14 secured thereon, the outer ends of said arm being crank and rod connected with cam 7^d, 80 by crank and rod connection 15. In this form of rotating means, the cam 7^d is rotated in the direction indicated by arrow 23, and is reversely inclined on axle 1'. The flexible member securing means thereon is 85 the same as seen in Figs. 4 and 5, but is placed as seen at 9^d, in Fig. 7. This is done because the rod and crank form of knuckle rotating means, does not act as a reverse rotating means, as is the case with all of the 90 previously described forms. The cam 7^d is therefore rotated in the direction indicated by arrow 23, as previously stated. It will be understood that cam 7^d is used in conjunction with a reversely inclined companion cam, not shown. The idle pulleys 13^a are rotatably mounted on frame 1^a, with a space between them. The rear end portions of flexible drawing members 12^a are passed around the inner surfaces respectively, of 100 said idle pulleys. This arrangement of the member guiding means, is essential in this form of mechanism, in order that the operating hand wheel, not shown, shall rotate in the same direction as wheel 11', seen in 105 Figs. 1 and 3. This being the conventional rotative direction of said hand wheel, the same should under all circumstances and in all forms of mechanisms be maintained for 110 obvious reasons.

Having fully described my invention, what I claim as new, and desire to secure by Letters Patent, is:—

1. In a steering mechanism for automobiles, a frame, knuckles pivotally attached to 115 said frame, elongated cams rotatably mounted distant from said knuckles, the curved faces of said cams being adapted to have flexible members wrapped thereon and secured thereto at certain points on said faces, 120 a flexible pulling member passed continuously around said cams, flexible drawing members having forward ends and rearward end portions, member securing means, one at a certain point on each of said cams 125 whereby the front ends of said drawing members respectively and said pulling member are secured to said cams, winding means mounted on said frame at a distance from said cams, said winding means being adapt- 130

ed to wind thereon and unwind therefrom
respectively the said rear end portions of said
drawing members, guiding means for said
drawing members, knuckle rotating means
5 connecting said cams and knuckles, and ve-
hicle wheels on said knuckles for supporting
said frame.

2. In a steering mechanism for automo-
biles, an elongated cam the curved face of
10 which is adapted to have flexible members
wrapped thereon said curved face having a
depression formed therein said cam having
a slot formed therethrough adjacent to said
depression, a flexible pulling member on said
15 depressed face, a flexible drawing member
having an end portion thereof on said de-

pressed face, a stirrup whereby said flexi-
ble members are pressed into said depres-
sion, securing means passed through the
ends of said stirrup and through said slot 20
whereby said stirrup is tightly secured in
place, a steerable vehicle wheel, movement
conveying means connecting said cam with
said wheel, and manually operated drawing
means connected with the other end portion 25
of said flexible drawing member.

In testimony whereof I affix my signature
in the presence of two witnesses.
